PROCESS OF PRODUCING LATERAL-
PROVIDED FITTINGS

Edward S. Cornell, Jr., Larchmont, N. Y.

Application January 24, 1939, Serial No. 252,516

3 Claims. (Cl. 113—44)

The invention is directed to the production of T's and other lateral-provided fittings of cold wrought integral metal.

The invention is of particular utility for the production of T's and other lateral-provided fittings by the cold working of material of the nature of copper, which is defined as including commercially pure, i. e., 99% or above, copper or other metal or alloy or like metallic constituency which under the condition of heat supplied thereto in advance of operation pursuant to the invention gives rise to the formation of cuprous or other oxid or other deleterious condition.

Pursuant to the instant invention, a shell, i. e., 15 a tubular blank having a closed end, in the absence of supplied heat, is suitably positioned in a suitable die, the die having apertures conforming to the configuration of the T or other lateral-provided fitting desired to be produced. In the instance of a T formed from such shell, the shell may be positioned within the "run," i. e., within aligned apertures of the die, a suitable pressure-exerting medium such as oil, water, plastic or the like being placed within the shell, and suitable means such as a press having or connected to a suitably shouldered plunger serving as a male die arranged to engage the material of the shell and subject the same to suitable mechanical pressure simultaneously with pressure internally of the shell engendered in the pressure-exerting medium, whereby the material of the shell at and adjacent the juncture of such aligned die apertures with a branch aperture of the die is caused to flow into and along the face of such branch aperture of the die, thereby forming the desired T or other lateral-provided fitting. Such pressure within the pressure-exerting medium may be engendered by the male die contacting such medium or by pipe connection with a suitable source of such medium under pressure.

It is desirable to positively support the material of the shell where unprotected by the faces of the die, against deformation either externally and/or internally.

It is also advantageous to employ a stop plug for limiting the extent of flow of the material of the shell into the branch die aperture. Such stop plug, most desirably, is provided with suitable facial configuration at its effective face, for imparting suitable contour at the terminus of the flowed metal, for facilitating suitable severing thereof, minimizing waste of metal severed, and the like.

In certain instances of carrying out the pres- 55

ent invention, the shouldered plunger may have a relatively elongated nose projecting into and approximately engaging the inner faces of the shell, thereby serving to support the material of the shell against inward deformation; such elongated nose at the stage of initial operation of the plunger may extend to the region of juncture of the branch aperture with the "run" apertures of the die. Also, such elongated nose of the plunger may be suitably apertured to provide for the path of flow of the pressure medium during the stage of movement of the elongated nose through the zone of the juncture of the die apertures. Such apertured elongated nose of the plunger, preferably, affords access of contact of the pressure medium with the portion of the material of the shell within the juncture of the branch apertures of the die, to thereby render more effective the flow of the material of the shell throughout the period of operation of the plunger in conjoint mechanical compressions at the open end of the shell upon the material of the shell.

Further features and objects of the invention will be more fully understood from the following detail description and the accompanying drawings in which

Fig. 1 is a central sectional elevation of a T, typical of a lateral-provided fitting producible pursuant to the present invention.

Fig. 2 is a central sectional elevation of a shell from which the T shown in Fig. 1 may be produced.

Fig. 3 is a central section elevation illustrating one method and suitable instrumentalities therefor for carrying out one form of the invention. Pursuant to such method a cut-away elongated nose is provided for the shouldered plunger; Fig. 4 is a central sectional elevation corresponding to Fig. 3, but showing a subsequent or final stage of the method; Fig. 5 is a sectional elevation on line 5—5 of Fig. 4.

Fig. 6 is a central sectional elevation of the product derived from my method such as pursuant to Figs. 3, 4 and 5. In Fig. 6 the left-hand and upper terminal portions of the material of the product are shown severed.

Fig. 7 illustrates in central sectional elevation a method of belling and providing abutment stops for one or more openings of the product shown in Fig. 6.

Fig. 8 is a central sectional elevation illustrating another form of my method for carrying out the invention; the parts here illustrated represent an initial stage of the operation; Fig. 9 is a

sectional elevation on line 9—9 of Fig. 8; and Fig. 10 illustrates a subsequent or final stage of the operation initiated in Fig. 8.

Referring to Figs. 2 through 5, of the drawings, an unheated, suitable shell of material of the nature of copper, above defined, such as the shell 10 having an open end 10a and closed end 10b, as illustrated in Fig. 2, is positioned in a suitable die 11, the lateral aperture of which is indicated at 11a and the aligned, i. e. "run" apertures are indicated at 11b and 11c. For the formation of a T, such shell 11 is advantageously positioned in the "run" apertures 11b, 11c, of the die 11, the closed end 10b of the shell resting on a face of the die aperture 11c. A 15 shouldered plunger is indicated at 12, its shoulder at 12a, and has a relatively long nose, see 12b, which is apertured as indicated at 12c to extend from its lateral face disposed toward or adjacent the lateral die aperture 11a, to and through its nose portion 12b'. It is observed that the projecting nose portion extends, when the plunger 12 is in its initial position, within the region of the juncture of the die apertures.

The diameter of the elongated nose 12b corresponds substantially to the inner dimension of 25 the shell 10.

It is noted from Figs. 3, 4 and 5, that the initial length of the shell 10 is less than the extent of "run" of the aligned die apertures 11b, 11c, and accordingly the outer faces of the shell 10 are 30 protected against outward deformation by engagement of the same with the faces of the aligned die apertures 11b, 11c.

As is shown in Figs. 2, 3, 4 and 5, it is advantageous to have the closed end 10b of the shell 10 flat.

Pursuant to my method illustrated in Figs. 3, 4 and 5, advantage is gained by positioning a stop plug 13 at the terminus of the lateral die aperture 40 11a, which stop plug is preferably provided with a convex effective face 13a, to thereby impart, as appears more fully hereinafter, a concave formation to the material of the shell cold-flowed into the lateral die aperture 11a. For affording release of air from the interior of the lateral die aperture 11a, the peripheries of the head and shank of such stop plug 13 approximate but roughly the diameter of the adjacent faces of the lateral die aperture 11a and its opening 11a'.

Upon positioning the shell 10 within the aligned die apertures 11b, 11c as indicated in Fig. 3, suitable pressure-exerting medium 14, above referred to, is placed within the shell to fill the same, when the long nosed plunger 12 is positioned to 55 dispose its shoulder 12a in engagement with the open end 10a of the shell.

The plunger 12 is then operated by a suitable press or equivalent, whereupon the material of the shell is subjected to mechanical pressure by engagement of the plunger shoulder 12a with the material of the shell simultaneously with pressure engendered within the pressure-exerting medium 14. The generation of such pressure within the pressure-exerting medium may be effected by the 60 engagement of the nose portions 12b, 12b', with the pressure-exerting medium or in lieu thereof the plunger 12 and the body of its elongated nose 12b may be bored to provide a channel for the flow of the pressure-exerting medium from a suitable source of pressure-exerting supply.

By such pressure applied mechanically to the material of the shell and concomitantly interiorly of the shell by the pressure-exerting medium, the material of the shell at and adjacent the zone of 75

the juncture of the die apertures is caused to flow into and within the lateral die aperture 11a, which operation may be continued until such cold-flowed material of the shell assumes a final 5 position as indicated in Fig. 4. It is observed that the projecting nose portion 12b initially and subsequently serves to preclude any inward deformation of the material of the wall, in co-action with the pressure engendered within the pressure-exerting medium 14.

Pursuant to the form of my method illustrated in Figs. 8, 9 and 10, the nose 12b of the shouldered plunger 12, at its initial position, as indicated in Fig. 8 may extend beyond the region of the juncture of the die apertures, to effect positive prevention of any deformation inwardly of the shell 10 throughout the area of juncture of the lateral die aperture 11a with the "rim" apertures 11b, 11c. The length of the elongated nose is preferably such that when the plunger 12 has moved to its final position, indicated in Fig. 10, spacing is provided between the end of the plunger nose and the closed end of the shell, to ensure full pressure effect of the pressure medium upon the material of and adjacent the closed end of the shell throughout the range of movement of the plunger. Otherwise, the method indicated in Figs. 8, 9 and 10, follows generically that illustrated in Figs. 3, 4 and 5, and referred to in particulars hereinabove.

The product derived by the above or equivalent procedure, in the instance of a T fitting, has the general T configuration 18 indicated in Fig. 6, namely having an open end at 18a, corresponding to the open end 10a of the shell 10, see Fig. 2, and closed at the respective ends 18b, 18c; in Fig. 6, the end terminal portions 18b' and 18c' are indicated as severed, as by means of a suitable saw.

It will be observed that the convex configuration of the stop plug 13, gives rise to a concave formation at the central portion of the terminal portion 18c', which, predicated upon practical experience, insures full attainment of the desired configuration at the terminal portions of the cold-flowed material, imparts rigidity thereto, effective during the severing operation, and other advantages, as appears.

In certain instances of use, as appears from Figs. 8 and 9, it is desirable to provide suitable means effective at the beginning of the stage of conjoint mechanical and internal fluid pressures to positively, i. e., mechanically preclude internal deformation of the material of the shell 10 throughout the zone of juncture of the die branch apertures, as by elongating the nose 12b of the plunger 12 to initially extend through and beyond the juncture zone, the intercommunicating apertures 12c, 12c, being arranged to provide a suitable path of flow for the pressure medium of access to the portion of the material of the shell, to be cold-flowed into the die aperture 11a, and preferably, as appears from Figs. 8 and 10, throughout the period of the stroke of the plunger 12.

The resulting general T product, having three open ends, may then be completed to commercial finish as may be desired. Usually, each end is provided with an abutment serving as a stop, indicated at 18d, for gauging the telescopic insertion of the end of a pipe or the like. The production of such stop 18d is advantageously carried out simultaneously with belling the ends of the T, as by means of a suitable expanding tool indicated at 19, in cooperation with a suit-

able two-part holding die 20. It is understood that, whereas Fig. 7 indicates but one end, i. e. 18a, expanded, either or both of the remaining ends 18b, 18c may be similarly treated.

The resulting T, see 21, Fig. 1 illustrates a T fitting of conventional internal and external configurations, and is adapted for connection with the end of a pipe or other fitting or the like, either by sweat-jointing, pursuant to conventional practice, or by threading, in which latter instance the wall thickness of each threaded end is sufficient to bear the necessary threading.

It is a characteristic of the present invention that my method, pursuant to any of the procedures hereinabove set forth, or equivalent, gives rise to an eventual T, the wall thickness of the respective ends, see 21a, 21b, 21c, is substantially uniform. In the embodiment illustrated in Fig. 1, the T is shown provided with abutments 21d in each of its connection openings 21a, 21b, 21c.

From the above, it appears that is of particular advantage in the formation of T's and other lateral-provided fittings, from a shell, by utilizing a female die having apertures conforming to the configuration of the T or other lateral-provided fitting desired to be produced, such shell being positioned within aligned apertures of the die, the closed end of the shell being in suitable abutting relation with a die face, in correlation with a shouldered plunger serving as the male die and provided with a nose having an effective diameter closely approximating the inner diameter of the shell, a suitable pressure-exerting medium being placed within the shell to fill the same, when the plunger is positioned to effect engagement of its shoulder with the open end of the shell, whereby upon application of pressure by such plunger, the material of the shell is caused to flow into the one or more desired branch apertures by the conjoint pressure mechanically applied by the plunger to the material of the shell and interiorly thereof by the pressure-exerting medium, the nose of the plunger being preferably elongated and apertured to provide path of flow for the pressure-exerting medium to facilitate flow of the material of the shell into such one or more branch die apertures.

Whereas I have described my invention by reference to specific forms thereof, it will be understood that many changes and modifications may be made without departing from the spirit of the invention.

I claim:

1. The method of producing a T or like lateral branch fitting from a closed-ended shell, which includes placing the shell in suitable die means having interconnecting branch apertures contoured to impart the desired configuration to the fitting, said shell being positioned within the run-forming apertures of the die and traversing the die aperture forming a lateral branch of said fitting, placing a flowable material within said shell, interiorly supporting said shell by means including an apertured rigid element disposed in slidable engagement with the interior wall of said shell over the full circumference thereof and up to and including a substantial area of intersection of said lateral branches of said die, engaging the peripheral wall of said shell by plunger means in operative association with said rigid supporting element, moving said plunger means and said rigid supporting element axially of said shell to exert endwise mechanical

pressure on the wall thereof thereby to effect supported flow of the material of said shell toward and into said lateral branch die aperture while concomitantly causing flow of said flowable material under pressure through said apertured supporting element to bear against said shell in the area of said lateral branch.

2. The method of producing a T or like lateral branch fitting from a closed-ended shell of metal, which includes placing the shell in suitable die means having interconnecting branch apertures contoured to impart the desired configuration to the fitting, said shell being positioned within the run-forming apertures of the die in contact with the walls thereof and traversing the die aperture forming a lateral branch of said fitting, supporting said shell against lateral movement in said die, placing a quantity of fluid within said shell, interiorly supporting said shell by means including an apertured rigid element disposed in slidable engagement with the interior wall of said shell over the full circumference thereof and up to and including a substantial area in the zone of intersection of the lateral branches of the die, confining said fluid within said shell adjacent the closed end thereof by means of said apertured supporting element, engaging the peripheral wall of said shell by plunger means in operative association with said rigid supporting element, moving said plunger means and said rigid supporting element axially of said shell to exert endwise mechanical pressure on the wall thereof, thereby to effect supported flow of the material and of said shell toward and into said lateral branch die aperture while concomitantly causing flow of said fluid under pressure through said apertured supporting element to bear against said shell in the area of said lateral branch.

3. The method of producing a T or like lateral branch fitting from a closed-ended shell of metal, which includes placing the shell in suitable die means having interconnecting branch apertures contoured to impart the desired configuration to the fitting, said shell being positioned within the run-forming apertures of the die in contact with the walls thereof and traversing the die aperture forming a lateral branch of said fitting, abutting the closed end of said shell against a wall of said die to preclude lateral displacement of said shell within said die, placing a quantity of fluid within said shell, interiorly supporting said shell by means including an apertured rigid element disposed in slidable engagement with the interior wall of said shell over the full circumference thereof and up to and including a substantial area in the zone of intersection of the lateral branches of the die, confining said fluid within said shell adjacent the closed end thereof by means of said apertured supporting element, operating upon the end of said shell by plunger means contacting the peripheral wall of said shell at the open end thereof, said plunger means being in operative association with said rigid supporting element, moving said plunger means and said rigid supporting element axially of said shell to exert endwise mechanical pressure on the wall thereof, thereby to effect supported flow of the material of said shell toward and into said lateral branch die aperture while concomitantly causing flow of said fluid under pressure through said apertured supporting element to bear against said shell in the area of said lateral branch.

EDWARD S. CORNELL, JR.
